Patented Oct. 14, 1913.

UNITED STATES PATENT OFFICE.

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT.

TELEPHONE PAY-STATION.

1,075,485.

Specification of Letters Patent.

Patented Oct. 14, 1913.

Application filed February 19, 1912. Serial No. 678,661.

To all whom it may concern:

Be it known that I, GEORGE A. LONG, a citizen of the United States, residing at Hartford, in the county of Hartford and 5 State of Connecticut, have invented certain new and useful Improvements in Telephone Pay-Stations, of which the following is a specification.

This invention relates to telephone pay 10 stations.

A telephone pay station involving my invention preferably includes in its make-up, a signal which may be of any suitable kind but which in the present case is of audible 15 type, and a telephone transmitter, and although the transmitter and the signal may be related in any desirable manner, I prefer that they be in resonant connection, by reason of which when the signal is operated, 20 such fact will through said transmitter and line, be transferred to a central office operator to indicate to her that toll has been paid or some equivalent necessary act performed. The signal to which I have 25 alluded may be operated in any suitable way, although I prefer that this be done by the person at the calling station or the individual who uses the pay station.

One of the primary objects of the invention is to provide means for preventing the operation of the signal until toll for 30 a message has been paid.

The device possesses many other features of novelty and advantage, which with the foregoing will be set forth at length in the following description wherein I will outline in detail one of the many forms of embodiment of my invention, this showing being provided to enable those skilled in the art 40 to practice the invention. From this it will be evident that I do not restrict myself to such showing; I may depart therefrom in several respects within the scope of the invention set forth in the claims following 45 said description. In the organization thus shown, as soon as a coin has been introduced into the machine the signal mechanism may be released and operated. In addition to this I provide for several calls 50 for one coin or it may be for a group of coins or for a given amount of money. The ordinary minimum charge for an outgoing local call is five cents. I provide for receiving a coin or coins of any denomina- 55 tion or denominations and to give in return

for the amount a specific number of calls. In the present instance the machine is adapted to receive a twenty-five cent piece, and the person who inserts such coin into the machine will be entitled to five calls, 60 although this will depend altogether on custom.

Referring to the drawings: Figure 1 is a front elevation partly in section, of a telephone pay station involving my invention. 65 Fig. 2 is a vertical sectional view of the same. Fig. 3 is a view of the mechanism inclosed by the casing, and, Fig. 4 is a front elevation of an indicator.

Like characters refer to like parts 70 throughout the several figures, which it will be perceived are on different scales.

The different parts of the device are preferably housed in a suitable casing such as that denoted in a general way by 5, and to which is connected the telephone transmitter 6, after the usual fashion in this art. As already intimated the signal may be of any suitable kind; that shown is denoted in a general way by 7 and consists of a gong 80 in resonant connection with the said transmitter. This gong may be struck in any suitable manner for example by the hammer 8 on the forward stroke of the plunger 9 which plunger extends through a hole or 85 perforation in the casing 5 so as to be accessible exteriorly of said casing. It might be added that the plunger 9 is advanced, to effect the action of the hammer 8 by the user of the station and that it is retracted by 90 a coiled spring 10 which with the gong and hammer are inclosed in the casing, being supported by the bracket 11. This bracket 11 also carries a register or counter 12, the plunger 9 having a lateral projection 13 95 adapted to enter between the branches of the fork 14 of an arm 14' connected with the register to thereby operate said register on each forward movement of the plunger or equivalent manually-operable member. 100 On the forward motion of the plunger 9 the hammer 8 is first swung out and then freed, at which point the operating spring for said hammer moves the latter quickly against the gong 7.

It is not a matter of importance as to what the denomination of the coin or coins is, the object in the construction shown being to introduce into the machine a certain amount of money which prepays for a cer- 110

tain number of calls, and although it is conceivable that several coins of different denominations might be simultaneously introduced into the machine, I have shown means 5 for simply supplying one thereinto, and although as previously intimated the denomination of this particular coin may vary, the parts are so proportioned as shown to receive a twenty-five cent piece. The means 10 for receiving a coin or coins may vary as to construction, although that shown and now to be described answers the necessary conditions. In the casing 5 there are two co-operating members such as 15 and 16 which 15 are adapted to be coupled by a coin or its equivalent, the part 15 serving to operate certain devices within the casing as will hereinafter appear, while the part 16 is directly operable by the user of the machine. 20 Unless a coin is employed to couple these two parts the part 15 cannot be operated when the part 16 is, a coin being necessary to effect such action. The parts 15 and 16 might be aptly considered as skeleton cylinders, the casing 5 having interiorly thereof, 25 means for rotatively supporting the outer cylinder 16, the inner cylinder 15 being fitted within the said outer cylinder, and both having slots which normally register 30 to receive the coin 17 which is adapted to be sustained temporarily by a rest as 18 carried by the outer cylinder. A runway as 19 leads to the normally registering slots in the parts 15 and 16 and from a slot 19' in one 35 side of the casing 5. It will be supposed that a coin is introduced into this runway. When it is, it travels down the same and enters the registering slots in the parts 15 and 16 thereby coupling said parts together so 40 that they can be moved as one, by operating in the present case, the outer cylinder or barrel 16 which latter it will be observed has an outwardly extending stud 20 supported for rocking motion in a bearing con- 45 stituting part of the casing 5. Said stud is shown equipped with a handle or lever 21 by which the same can be conveniently operated and which bears normally against a stop 22 on the casing at which time the 50 slots of the two parts 15 and 16 coincide. The inner cylinder 15 is shown provided with an inwardly extending stud or pivot 23, the casing 5 interiorly thereof being provided with a bearing for supporting said 55 stud 23 for turning movement. It follows that when the parts 15 and 16 are coupled together by a coin and that when the arm 21 is swung down or otherwise operated, to impart a half turn to the outer cylinder or 60 barrel 16, the inner barrel 15 is given a corresponding movement, and when the half turn has been completed the coin 17 will drop from the two parts into the usual coin box 24 in the bottom portion of the 65 casing 5.

The machine preferably includes indicating means which in the present case shows both the amount of money that is in the machine and also the number of calls to which a subscriber may be entitled, although neither or both is essential. Although said indicating means may be of any convenient kind it is shown as comprising an indicating member such as 25 graduated from zero to 60, each graduation representing five cents 70 or one call. In connection with the indicating member is a pointer or finger 26, the shank of which extends through and moves longitudinally of registering slots 27 in the indicating member 25 and casing 5 respectively being connected with a carriage as 28 which in the present case has a movement transversely of the casing 5, being preferably operated as will hereinafter appear, in one direction through the primary agency 80 of the plunger 9 or its equivalent, and in the other direction through the primary agency of the coin-controlled mechanism to which I have already alluded or in some similar manner. As shown this carriage is 85 supported by parallel shafts 29 and 30 sustained by suitable bearings in the casing and extending transversely thereof, the shaft 29 being shown as a screw while the shaft 30 is plain. Connected rigidly with the said carriage 28, is a nut 31 in engagement with the threaded portion of the screw shaft 29, said nut fitting an opening in the carrier 28 and being held in place by the nut 32. The holding nut 32 engages the feed 95 nut 31 at one end thereof, said feed nut having at the opposite end the pinion 33. From this it will be clear that when the feed nut 31 is moved longitudinally of the shaft 29 by rotating the latter, the carriage 28 will be similarly operated and at the same time will move longitudinally of the parallel supporting and guide shaft 30. In the construction shown the pinion 33 is in mesh 100 with the gear 34 splined to the shaft 30 and the hub of which fits in the upper portion of the said carriage 28 and is held in place by the nut 35. Pinned or otherwise suitably connected with the stud 23 is a gear 36 in mesh with the pinion 37 fastened suitably 105 to one end of the shaft 38 supported by bearings in the casing 5. This shaft 38 also carries the gear 39 in mesh with the pinion 40 on one end of the screw shaft 29. Suitably fastened to the shaft 30 is a ratchet wheel 110 41 engageable by the pawl 42 pivotally carried by the rocker 43 loosely carried by the shaft 30. To the rocker is shown loosely connected the arm 44 fastened in some suitable manner to the rock shaft 45 to which is 115 also rigidly connected the arm 46 connected by a loose joint to the inner end of the plunger or equivalent member 9.

It will be assumed that a twenty-five cent piece 17 has been inserted in the machine 130

and is resting on the support 18, and that the members 15 and 16 are, therefore, coupled together by such coin. In this event said parts 15 and 16 can be operated as one by 5 the handle 21, and on such movement the said parts 15 and 16 will be given a half rotation and when they are inverted the quarter 17 will gravitate therefrom and thereby uncouple said parts. It will be understood that although the inner cylinder has 10 a continuous step-by-step movement always in the same direction, the outer cylinder is capable simply of a half turn being limited by the stop 21 already described and the 15 companion stop 21'. On the turning of the inner cylinder 15 the stud 23 is given a similar movement, and the screw shaft 29 through the interposed gearing already described is correspondingly moved whereby 20 the carriage 28 will be advanced or as shown, moved to the right in Figs. 1 and 3. If prior to the operation already described the pointer 26 was opposite zero on the indicating member or scale 25, said pointer at the 25 conclusion of said operation would be opposite the five mark. If a second quarter were introduced the pointer through the movement of the carriage and the parts already described, would be carried to the ten mark. 30 on the pointer and so on, so that if twelve quarters were employed the pointer would finally be opposite the sixty mark, indicating that \$3.00 was in the machine, and in such a case the carriage 28 would be shifted 35 to the extreme advanced position and would remain in this position or in any intermediate advanced position until the signal 7 was operated on making a call.

It will be assumed that coin is in the 40 machine and that a call is to be made. In making a call the central office operator requires the subscriber to operate the signal, and before the signal can be operated it is necessary to thrust the plunger 9 rearward.

45 On such motion of the plunger the pawl 42 through the intermediate described parts is moved one step thereby imparting a corresponding movement to the ratchet wheel 41 and therefore rotating the shaft 30. On 50 said movement of said shaft the gear 34 and hence the gear 33 and nut 31 will be similarly operated so as to retract said nut 31 and therefore the carriage 28, the latter being retracted or drawn backward one step 55 and consequently moving the pointer 26 from a higher toward a lower number on the scale 25. If the pointer happened to be opposite the five mark on the scale, the same would be moved opposite the four mark on 60 said scale when the operation just described was concluded. It will be assumed that there is twenty-five cents in the machine. When each call is made the carriage 28 is retracted one step, and when the five calls 65 have been made the gear 34 will be brought

substantially and solidly against the hub of the gear 41 so as thereby to effectually lock the ratchet 41 against movement and therefore prevent the plunger 9 from being moved to effect the operation of the signal 7, it being necessary to insert a coin before the signal mechanism can be operated. 70

I have described in detail the construction shown in the accompanying drawings, which is highly advantageous. I wish to make it 75 clear that I can depart from this construction in many respects. I may if desired provide means for handling coins of different denominations.

Although the counter or register 12 is desirable, it like certain other parts already described, may in some cases be omitted and in similar manner equivalents may be employed instead of certain of the members already described within the scope of my invention. A register or counter, however, is advantageous in that a check is had upon the subscriber, so that the subscriber must of necessity pay for the calls which have been registered notwithstanding the fact that a 90 slug or slugs may have been used in obtaining one or more of such calls.

What I claim is:

1. A telephone pay station comprising a signal, means for locking said signal against action, an indicator, manually operable means for releasing said signal and for also operating said indicator, and independent manually operable means for also operating said indicator. 95

2. A telephone pay station comprising a telephone transmitter, an audible signal to transmit sounds through said transmitter, means for locking said signal against action, an indicator, manually operable means for releasing said signal and for also operating said indicator, and independent manually operable means for also operating said indicator. 105

3. A telephone pay station comprising a signal, means for normally preventing action of said signal, an indicating device, manually operable means for moving said indicating device in one direction and for also releasing said signal, and independent manually operable means for moving said indicating device in the opposite direction. 115

4. A telephone pay station comprising a signal, an indicating device, manually operable means for moving said indicating device in one direction, and independent manually operable means for moving said indicating device in the opposite direction, one of said manually operable means being adapted to effect the action of said signal. 120

5. A telephone pay station comprising a signal, means for normally preventing action of the signal, an indicating device, manually operable means for advancing said indicating device and for also releasing the signal, 130

- and independent manually operable means for retracting said indicating device and for also effecting the operation of said signal.
6. A telephone pay station comprising a telephone transmitter, an audible signal in coöperative relation with said telephone transmitter, an indicating device, manually operable means for moving said indicating device in one direction, and means for operating the signal, and operatively connected with said indicating device for moving the same in the opposite direction.
7. A telephone pay station comprising a signal, an indicating device, and independent manually operable means for imparting separate movements to said indicating device, and one of them connected with the signal for operating the latter.
8. A telephone pay station comprising a telephone transmitter, an audible signal in resonant connection with said transmitter, an indicating device, signal operating mechanism provided with means for moving said indicating device in one direction, and manually operable means for moving said indicating device in the opposite direction.
9. A telephone pay station comprising a signal, indicating means, manually operable means for operating the said indicating means in one direction, and signal operating means for moving said indicating means in the opposite direction, said indicating means being adapted also when in one position to prevent the action of the signal.
10. A telephone pay station comprising a signal, an indicating device, manually operable means for operating said indicating device in one direction, and signal operating means for moving said indicating device in the opposite direction, said indicating device having means adapted when the same is in one position, to prevent the action of said signal operating means.
11. A telephone pay station comprising a signal, a traveling carriage provided with a pointer, manually operable mechanism for moving said carriage in one direction, and signal operating mechanism having means for moving said carriage in the opposite direction.
12. A telephone pay station comprising a signal, a traveling carriage provided with a screw, a rotary shaft in engagement with said screw, means for turning said shaft in one direction, independent means for operating the signal and for also turning said shaft in the opposite direction, and a pointer connected with said carriage.
13. A telephone pay station comprising a signal and a casing provided with a scale, a pointer in coöperative relation with said scale, signal operating mechanism provided with means for operating said pointer in one direction, and manually operable means for moving said pointer in the other direction.
14. A telephone pay station comprising a signal, indicating means including a scale, and a pointer, one of which is movable with respect to the other, manually operable means for shifting the relatively movable member of the indicating means in one direction, and signal operating mechanism provided with means for moving said relatively movable member in the opposite direction.
15. A telephone pay station comprising a signal, a pair of shafts, one of which is in the form of a screw, a carriage supported for movement by said shafts and having a nut in engagement with the screw shaft, manually operable means for rotating the screw shaft, and signal operating means for rotating the companion shaft, the two shafts being intergeared.
16. A telephone pay station comprising a signal, a pair of shafts, one of which is in the form of a screw, a carriage supported by said shafts and having a nut engageable by the screw shaft, manually operable means for rotating said screw shafts, signal operating mechanism provided with means including a pawl and ratchet for rotating the companion shaft, the two shafts being intergeared, and indicating means comprising a movable member supported by said carriage.
17. A telephone pay station comprising a telephone transmitter, an audible signal in resonant connection with said transmitter, a manually operable device provided with means for sounding said signal, a pair of shafts one of which is a screw shaft, a carriage supported for traveling movement by said shafts, the shafts being intergeared, manually operable means for rotating the screw shaft, a ratchet wheel fastened to the companion shaft, a pawl for operating said ratchet wheel, and means actuated by said manually operable member for moving the pawl to operate said ratchet wheel.

In testimony whereof I affix my signature in presence of two witnesses.

GEORGE A. LONG.
